ICE CUBE CARRIER

George F. Kearney, New York, N. Y., assignor
of one-half to Edward Maynard Reilly, New
Rochelle, N. Y.

Application October 14, 1932. Serial No. 637,694

10 Claims. (Cl. 65—5)

The main object of my invention is to provide a simple and convenient means for carrying small ice cubes in a manner so that they can be conveniently handled without freezing together.

Another object is to provide a construction which is sanitary and can be readily cleaned.

Another object is to provide a construction in which the water will drain away from the melting ice.

Another object is to prevent sweating of the base of the carrier.

Another object is to provide means for preserving the ice and keeping it clean and sanitary.

In carrying out the invention I provide a tray having a series of individual pockets for receiving the respective ice cubes. These pockets are provided with individual means for draining water away from the ice and a bottom pan is provided for receiving and holding the water at the bottom. An additional tray serving as a base is provided which is free from the effects of condensation. The various parts of the carrier are preferably detachably connected together so that they can be readily separated and assembled. A hood or protecting case may also be provided to enclose a number of the cubes and their respective shelves or pockets.

In the drawings I have illustrated a carrier which is substantially rectangular in plan view but it should be understood that the design may be modified and the carrier made generally polygonal or cylindrical in plan.

Fig. 1 is a perspective view of one form of carrier involving my invention.

Fig. 2 is an end and transverse sectional view of the same.

Fig. 3 is a perspective view showing fragments of the water holding tray and the base and a latch for connecting them.

Fig. 4 is a fragmentary vertical section showing a latch for connecting the pocket member and its tray.

Fig. 5 is a side view and partial vertical section of the form shown in Fig. 1.

Fig. 6 is a perspective view showing a modification having an enclosing protecting case.

Fig. 7 is a perspective view showing a fragment of a modification of the carrier.

Fig. 8 is a fragmentary perspective view showing a modified form of shelf.

The frame 10 may be made in many different ways, for instance, of sheet metal and preferably with oppositely inclined sides. To these sides are attached a number of rows of pockets formed,

for instance, by shelves such as 11, 12 and 13 and partitions such as 14 which divide the shelves into discrete pockets adapted to hold individual cubes of ice and thus prevent them from freezing together. These shelves preferably project from the inclined sides at right angles so that the cubes are supported by the inclined walls and the inclined sides, thus maintaining the shape of the cubes as they melt.

The rear edges of the shelves are preferably provided with passages 15 constituting means for draining the respective pockets so that the cubes will not stand in water.

The frame is supported in a tray or pan 16 adapted to contain the water from the melting cubes. This frame is preferably detachably secured in the tray so as to permit separation of the parts for the purpose of cleaning. Various forms of latch mechanism may be employed for securing the frame in the tray such, for instance, as the spring pressed latch 17 which is secured to the tray and engages in the end of the frame. The bottom of the frame is also preferably positioned in the tray by stops 18 of any suitable form.

The upper end of the tray is provided with a suitable handle 19 for convenience in carrying the device.

On account of the fact that moisture is likely to condense on the outside of the tray 16 I preferably provide some form of protecting base as, for instance, the supplemental tray or pan 20 so as to provide an air space. The tray 16 is preferably detachably mounted in this base tray 20 in any suitable manner as, for instance, by means of studs 21 and 22 carried by the tray 16 and adapted to fit into angular slots 23 and 24 in the opposite edges of the tray 20. A pivoted latch 25 may be provided for detachably holding the two members together so that the parts may be separated for the purpose of cleaning.

For sanitary reasons it may be desirable to enclose the ice by a suitable housing or external casing arranged, for instance, in the form of cover members 26 and 27 hinged at 28 to the sides 100 of the main frame. These cover members may also be provided with thermal insulation if desired to preserve the ice from melting, especially in very warm climates.

The main frame for supporting the pockets may be formed in many ways, for instance, as shown in Fig. 7 where the frame 30 is formed of sheet metal with oppositely inclined sides connected along the top 31. The shelves 32 may be formed by stamping out portions of the sides and

providing them with integral flanges 33 and leaving drainage passages 34.

The pockets might also be formed as shown in Fig. 8. In this case a shelf 35 of sheet metal is provided with a rear flange 36 adapted to be secured to the main frame in any suitable manner as for instance by means of key hole slots 37 adapted to engage conventional studs (not shown) so that the shelf will be detachable. The shelf may be divided into a series of pockets, for instance, by ribs 38 punched or drawn from the material of the shelf.

For convenience in illustration and description I have shown a carrier with three shelves on each side, each shelf having three pockets so that the device will accommodate eighteen cubes of ice.

Obviously the size of the device and the number of pockets are immaterial to the invention. It should also be understood that the invention is not limited with respect to the number of shelves or the shape of the frame. Usually it will be polygonal so as to more conveniently accommodate the usual ice cubes.

In some cases it may be desirable to provide supplemental means for refrigeration so as to prevent the cubes from melting too rapidly while being transported from the freezer to the user. For this purpose the interior of the frame 10 might be filled or partially filled with solidified carbonic dioxide, commonly termed "dry ice".

By inclining the shelves the cubes are held in place by gravity but in such a way that they can be readily removed when desired.

The frame may also be provided with supporting hooks 40 at opposite ends to accommodate suitable implements, for instance, ice tongs or a bottle opener.

Other changes may be made in the construction and arrangement of parts without departing from the spirit or scope of my invention.

I claim:

1. An ice cube carrier comprising a frame having a plurality of tiers of shelves with obstacles forming discrete cube-holding pockets, said shelves being provided with self-draining outlets and a water tray beneath the pockets.

2. An ice cube carrier comprising a frame having a plurality of tiers of shelves with obstacles forming discrete cube-holding pockets, said shelves being provided with self-draining outlets, a water tray beneath the pockets, and a protecting cover for the shelves.

3. An ice cube carrier comprising a frame having a handle at the top and having discrete self-

draining cube-holding pockets, and a water-receiving tray carried by said frame beneath the pockets, and a second tray detachably connected to the first and spaced apart beneath it to leave an air space.

4. An ice cube carrier comprising a frame having a handle and having discrete ice cube-holding pockets, a water-holding tray beneath the frame and pockets and a detachable protecting base for the tray with an air space between the base and tray.

5. An ice cube carrier comprising a frame having a series of detachable ice cube-holding pockets, a water tray surrounding the base of the frame, and an air-holding tray spaced apart beneath the water tray to prevent condensation of moisture at the exposed bottom.

6. An ice cube carrier comprising a frame having discrete ice cube-holding pockets, a protecting housing for the pockets formed of two portions hinged at opposite ends of the frame, and a base comprising a tray beneath the pockets and housing provided with an air chamber to prevent condensation of water on the outside of the base.

7. An ice cube carrier comprising a frame with a handle at the top and having a number of rows of inclined shelves with partitions forming discrete ice cube-holding pockets having drainage outlets at the bottom of the pockets and an air insulated drip-receiving tray beneath the pockets.

8. An ice cube carrier comprising a frame having two rows of oppositely disposed discrete self-draining cube-holding pockets, a water-receiving tray carried by said frame beneath the pockets, and a second tray beneath the first with an air space between the trays to prevent condensation of moisture beneath the carrier.

9. An ice cube carrier comprising a frame having ice-holding pockets and a water pan, and a cover member hinged to the ends of the frame for enveloping the ice pockets and an air holding base beneath the water pan to prevent condensation of moisture on the bottom of the carrier.

10. An ice cube server comprising a water-receiving tray forming a base, a standard mounted on the tray and having a handle at the top and a series of shelves arranged one above another on opposite sides of the standard and provided with discrete cube-holding pockets having drainage outlets near the standard.

GEORGE F. KEARNEY.
